Grace E. Almqquist,
INVENTOR.

BY Victor J. Evans,

ATTORNEY.

WITNESS:

B. White.

UNITED STATES PATENT OFFICE.

GRACE E. ALMQUIST, OF LA PORTE, TEXAS.

FRUIT-JAR RING.

Application filed February 10, 1923. Serial No. 618,353.

To all whom it may concern:

Be it known that I, GRACE E. ALMQUIST, a citizen of the United States, residing at La Porte, in the county of Harris and State of Texas, have invented new and useful Improvements in Fruit-Jar Rings, of which the following is a specification.

This invention relates to fruit jar rings and has for its primary object the provision of a ring which will be strong and durable and structurally designed to hermetically seal a preserving jar or similar receptacle and to permit the seal to be quickly broken and the cap of the jar removed without the aid of a cap wrench or the like.

A further object of the invention is to provide a ring having a plurality of diametrically disposed lips formed as an integral part of the body of the ring and adapted to be pulled manually to unseal portions of the ring from beneath the cap, the construction and arrangement of the lip being such as to cause uniform strains to be applied to the body of the ring when breaking the seal, whereby to prevent casual tearing away of the lip from said body portion of the ring.

With these and other objects in view, the invention resides in certain novel construction and combination and arrangement of parts, essential features of which are herein-after fully described, are particularly pointed out in the appended claim, and are illustrated in the accompanying drawing, in which:—

Figure 1 is a plan view of the ring.

Figure 2 is a vertical section through a jar showing the cap sealed against the ring.

Figure 3 is a similar view demonstrating the manner of breaking the seal.

In carrying the invention into practice, I use any suitable well-known form of preserving jar 1 having a threaded neck 2 and a correspondingly threaded cap 3, the latter being flanged at 4 to coact with a shoulder 5 of the jar.

My improved ring 6 is formed of elastic material and is adapted to be placed over the neck of the jar against the shoulder

5 so that the flange 4 of the cap 3 can be brought into sealing contact therewith. The said ring 6 is provided with diametrically disposed lips 7, 7 which are exposed from the sides of the shoulder 5 when the cap 3 is in its sealed or closed position. The annular body of the ring is superposed with respect to the shoulder 5 and when it is desired to break the seal and remove the cap 3, the lips 7, 7 are uniformly pulled outward so as to remove portions of the annular part or body of the ring from beneath the flange 4. This permits atmospheric air to enter the jar and in practice it is possible that the cap 3 can be unscrewed from the neck of the jar without the aid of cap engaging wrenches or tools. By providing lips 7, 7 diametrically positioned upon the ring the said lips are made to take the pulling strains proportionally and these strains are correspondingly distributed around the annular body of the ring. This prevents casual tearing away of the lip from the ring as will be understood. In order to further safeguard against casual separation of the lips from the body of the ring, I may extend flexible reinforcing strips 8 around the lips as at 9 embedding the same therein and passing and embedding the terminals 10 of said strips in the annular body of the ring. This gives reinforcement to the lips at their joinder with the annular body of the ring and at the same time does not interfere with expanding the diametrically opposite sides of the ring when breaking the seal. Concavo-convex openings 11 are formed in the lips in a manner whereby the thumb or finger of the person removing the seal may be inserted therein to effect a firm purchase with the lips.

The lips 7 are preferably provided with apertures 11 whereby the lips may be firmly grasped when secured between the fingers when expanding the ring.

While I have described what I deem to be the most desirable embodiment of my invention, it is obvious that many of the details may be varied without in any way departing from the spirit of my invention, and I therefore do not limit myself to the exact

details of construction herein set forth nor to anything less than the whole of my invention limited only by the appended claim.

What is claimed as new is:—

• A fruit jar ring consisting of an annular body of elastic material provided with integral diametrically disposed lips provided

with concavo convex openings arranged therein, and reinforcing strips associated with the lips and with the annular body of 10 the ring respectively.

In testimony whereof I hereby affix my signature.

GRACE E. ALMQUIST.
